MOP CONSTRUCTION

Burton A. Olsen, Oakland, Calif., assignor to California Cotton Mills Company, Oakland, Calif.

Application March 6, 1943, Serial No. 478,237

4 Claims.

(Cl. 15—229)

This invention relates to mops, and particularly to the kind of mops in which the head is made up of lengths of cords secured to one end portion of a stick.

One of the main objects of the invention is improved construction of the mop head in which the cords forming the head are more securely held on the stick than heretofore, and which construction makes possible very rapid and economical making of mops with a minimum of metal or other elements that have heretofore been employed.

Other objects and advantages will appear in the description and drawings.

The particular structure comprising this invention will be more clearly understood by stating at this time that the web of cords from which the mop head is made is not new in itself. The invention resides in the construction resulting from the manner in which the web is secured to the stick. The web itself is made in a conventional manner in which relatively long cords are wound around a pair of generally parallel spaced strings to form a skein-like band of cords and which are later severed along a line between the strings and parallel therewith. Whether the cords of such skein are severed before or after securement to the mop stick, or the particular manner in which the web of cords for each mop is fabricated is not a part of this invention. It is sufficient that the mop structure of this invention employs a band-like web of cords folded over a string that extends along one edge of the web where the cords are folded over the string. These cords may each be made up of a plurality of rope-like lengths, and in Figs. 1 to 6 of the drawings hereinafter described, it is to be understood that the cords are diagrammatically indicated, for clarity, without attempt to illustrate any winding characteristics of strands making up the cords.

In the drawings,

Fig. 1 is an elevational view of a mop head on the outer end of a mop stick.

Fig. 2 is an elevational view of the outer end portion of a stick to which the head is to be attached.

Fig. 3 is a part sectional, part elevational view of a portion of a web of cords that is used to make up the mop head, it being understood that in actual practice, the web portion is as long as is found to be necessary and the cords are of any desired length.

Fig. 4 is an elevational view of the outer end portion of the mop stick; the web being shown at the beginning of the winding step in the formation of the mop head and its securement to the stick.

Fig. 5 is a second elevational view generally similar to that of Fig. 4 in which the development

of the mop head is at a stage slightly beyond that shown in Fig. 4.

Fig. 6 is a sectional view through the mop head just before the final step of securing the head to the stick. Fig. 1 shows the completed stage.

Fig. 7 is an enlarged, fragmentary elevational view of rope-like lengths of the material that may make up each of the cords that is diagrammatically indicated in the preceding views.

10. In detail, the mop stick 1 is provided at one side of its outer end portion, and spaced from the terminating end of the stick, with a pin, tack or nail 2 projecting from said side (Fig. 2). This pin provides one type of means for securing one

15. end of the web of cords thereto.

The band-like web of cords for forming the mop head comprises a stout string, generally designated 3, having a row of cords 4 folded thereover, said string extending along one edge of the

20. web and supporting said cords thereon, and string 3 projects at its ends from the ends of the web.

25. One projecting end portion 5 of said string is secured, as by tying, to the pin 2 at a point spaced a sufficient distance from the first cords on said web to enable winding the portion of said string that is between said pin and said first cords several times around the end portion of the stick 1 outwardly of pin 2 before the first cords of the web are brought into contact with the stick. This end portion 5 between pin 2 and the cords at the end of the web nearest the pin is tightly wrapped in a spiral coil around the end portion of the stick outwardly of pin 2, which coil extends from the pin toward the terminating end 30. of the stick adjacent the pin. Thus the cords of the web at the end of the latter nearest the pin will initially be brought into engagement with the outer end portion of the stick at a point spaced from the pin and fairly close to the end 35. of the stick.

At substantially the time when the cords of the web at the end of the latter nearest the pin come into engagement with the side of the end portion of the stick, the direction of the spiral-coil winding is reversed, although the rotation

40. remains the same, and the edge of the web along the string is wound back over the portion 5 of the string in a spiral coil that extends past the pin a distance toward the handle end of the stick. When the last cords of the web, or those most remote from end 5 of the string come into tight engagement with the side of the stick along the edge of the web that is supported by the string, the other projecting end portion 6 of the string

45. is brought back over the cords in a spiral-coil winding to a point or position about over the pin 2, but preferably slightly beyond the pin toward the terminating end of the stick adjacent said pin, and at this point the adjacent coils of the 50. spiral-coil of the string are close together, as

indicated at 1 (Fig. 1). As soon as this coil 1 is completed, the remaining end portion of the string is tucked under the coil 1 to hold it in place and to secure the coil 1 from becoming loosened.

At about the commencement of the winding of the web on the end portion of the stick, one of the cords 8 of the web (Figs. 4, 6) is preferably wound around the first layer or so of the cords outwardly of the end of the stick to close said end so that the stick will not contact the surface to be cleaned by the mop head. After such layer or layers are secured over the end of the stick, the outer end of cord 8 may be laid alongside the outer end portion of the stick for securing to the stick below the remaining coils of the web that are wound around the end portion of the stick. There is no claim made to this particular feature in itself since heretofore cords in mop heads have been secured over the end of the mop stick by one of the cords of the mop head for the same purpose.

By the foregoing structure it is seen that each of the cords of the web is tightly secured directly against the side of the mop stick by the string supporting the web, which would not be the case were a layer of the cords to be interposed between the stick and one of the coils of the web along the edge that is supported by the string. This structure materially contributes to the tight securing of the head to the stick.

Another important feature of my invention is the spiral-coil winding of the web at the edge thereof along the string in a direction from the outer end of the stick toward the handle and past the pin. This also materially contributes to the tight securing of the mop head to the stick since direction in which the coil is formed at both sides of the pin 2 insures against any possible slippage of the head on the stick away from the end of the stick in either direction longitudinally of the stick or transversely thereof.

The final winding of the end portion 6 of the string over the coils of the web where the latter are coiled around the stick and over the pin that is concealed below said coils, is another feature that further contributes to the stability of the mop head on the stick.

In the claims, where the term "spirally" is used to designate the manner in which the web is wound on the stick, it is intended to define a spiral coil the inner sides of which substantially follow the cylindrical contour of the end of the stick, as distinguished from a spiral in which the sides taper axially of the coil to follow a different contour than that of the outer sides of the stick, or in which the successive coils are in a single plane developed about a single center.

Having described the invention, I claim:

1. A mop comprising a stick providing a handle adjacent one end thereof and a support for a mop head adjacent its opposite end, a mop head comprising a string and a continuous row of cords folded thereover providing a band-like web of cords suspended from said string with the opposite end portions of said string projecting from opposite ends of said web, one of the said end portions of the string being secured to said stick at a point adjacent but spaced from said opposite end, the part of said string carrying said cords being spirally wound on said stick

a plurality of turns in direction generally away from said opposite end and toward said handle, the other end portion of said string being wrapped around the outer sides of said web substantially over said point securing said web against loosening.

2. A mop comprising a stick providing a handle adjacent one end thereof and a support for a mop head adjacent its opposite end, a mop head comprising a string and a continuous row of cords folded thereover providing a band-like web of cords suspended from said string with the opposite end portions of said string projecting from opposite ends of said web, one of said projecting end portions of the string being secured to said stick at a point adjacent but spaced from said opposite end thereof, and spirally wound on said stick from said point toward the said opposite end, the said web being spirally wound on said stick from said end and a distance past said point in a direction toward said handle, and the other end portion of said string being wound around the outermost sides of said web and substantially over said point securing said web against loosening.

3. A mop comprising a stick providing a handle adjacent one end thereof and a support for a mop head adjacent its opposite end, a mop head comprising a string and a continuous row of cords folded thereover providing a band-like web of cords suspended from said string with the opposite end portions of said string projecting from opposite ends of said web, one of said projecting end portions of the string being secured to said stick at a point adjacent but spaced from said opposite end thereof and spirally wound on said stick from said point toward the said opposite end of the stick, the said web being spirally wound on said stick from said end and a distance past said point in a direction toward said handle, and the other end portion of said string being wound around the outermost sides of said web and substantially over said point securing said web against loosening; a pin securing said first mentioned end portion of the string to said stick at said point.

4. In a mop having a stick and a mop head secured to one end portion thereof, said mop head comprising a string and a row of cords folded thereover providing a band-like web of cords with said string extending along one edge of the web and supporting said row of cords, a pin secured on said end portion of the stick at one side thereof and spaced from the terminating end of the stick adjacent thereto, one end of said string adjacent one of the ends of said web being secured to said pin, the part of said string supporting said cords being spirally wound around said end portion of the stick in direction away from said terminating end of the stick, and the end portion of said string adjacent the opposite end of said web being wrapped on itself and about said web thereby securing said end portion of the string in place relative to the stick and securing said web against loosening, the said end of the string that is secured to said pin extending spirally around said stick from said pin toward said terminating end of the stick and the opposite end of the said string that is wrapped on itself being positioned substantially over said pin.

BURTON A. OLSEN.
